UNITED STATES PATENT OFFICE

MATTHEW R. BOYLAN, OF JERSEY CITY, NEW JERSEY, ASSIGNOR TO PUBLIC SERVICE COORDINATED TRANSPORT, OF NEWARK, NEW JERSEY, A CORPORATION OF NEW JERSEY

DESIGN FOR A FARE TOKEN

Application filed January 10, 1930. Serial No. 34,095. Term of patent 14 years.

To all whom it may concern:

Be it known that I, MATTHEW R. BOYLAN, a citizen of the United States, residing at 159 Fairview Ave., Jersey City, in the county of Hudson and State of New Jersey, have invented a new, original, and ornamental Design for a Fare Token, of which the following is a specification, reference being had to the accompanying drawing, forming part hereof.

In the drawing—

Figure 1 shows the obverse face of the fare token.

Figure 2 shows the reverse face of the fare token.

I claim:

The ornamental design for a fare token as shown.

MATTHEW R. BOYLAN.
